FLUID CONTROL VALVES

Stanley Grapes Shand, Hereford, England, assignor to
Saunders Valve Company Limited, Monmouthshire,
England, a British company

Application June 6, 1955, Serial No. 513,558

10 Claims. (Cl. 251—174)

This invention relates to fluid control valves such as plug cocks of the kind having the joint between the obturating member and the body of the valve made by means of at least one seating ring supported against the obturating member by a flexible diaphragm sealed to the obturating member and sealed at its periphery within the body and exposed on its outer surface to fluid pressure, pressure of the seating ring upon the obturating member being maintained in the absence of fluid pressure by spring means.

In the specification of Patent No. 2,520,288 a plug cock of the above kind is disclosed in which the plug, conveniently of spherical form, rotates between seatings which are separate from the cock casing and free to rock a little about the axis of the plug.

A development is disclosed in the specification of my application Ser. No. 73,238 filed January 28, 1949 now Patent No. 2,751,185 in which to enable a diaphragm of convenient size to be used without excessive fluid pressure acting on the seatings an annular abutment surface is provided rigid with and extending inwardly from the internal surface of the valve body and of such radial width that its internal diameter is less than the external diameter of the seating ring, this abutment surface being located next to the diaphragm on the plug side; thus a corresponding part of the fluid pressure on the diaphragm is transmitted to the abutment surface and not to the seating ring. This specification also discloses further reduction of the fluid pressure acting on the seating ring by counter-boring the ring so as to expose its plug side to the fluid pressure and counterbalance part of the pressure exerted by the diaphragm, and it was proposed to make the counter-bore of such diameter as to reduce the effective fluid pressure to zero.

Where plug cocks of this kind are used in lines in which very high pressures are likely to be developed, for example fuel lines on aircraft where very large temperature changes are encountered, it has been found necessary to provide means for allowing excessive pressures to be released to avoid damage to components, joints, piping etc. According to the present invention, in a plug cock of the kind above set forth the fluid pressure also has access to the plug side of the ring over an area greater than the area over which the pressure is effective on the back of the diaphragm to press the ring towards the plug so that the net effect of fluid pressure is to lift the ring away from the plug and the necessary seating pressure is provided by springs strong enough to ensure a good joint under normal operating conditions. When the valve is closed, if pressure on one side rises above a predetermined value the fluid will force its way between the ring and the plug into the body space of the valve, thus relieving the pressure in the line. Considerable relief can be obtained in this way due to the relatively large clearance volume in the body space, but if the pressure in the body space builds up to a higher value than that on the lower pressure side, by giving the fluid access to the plug side of the diaphragm over an adequate area, the

2

pressure will overcome the spring pressure and force its way between the diaphragm and the ring, thereby escaping to the low pressure side of the valve.

It will be seen that the relief of pressure does not involve discharge of liquid outside the valve and the line, a point of some importance where highly inflammable fluids such as petrol are being controlled. It will be understood that the line itself must permit pressure relief on one side of the valve but usually the line on one side of the valve is open to the atmosphere at some point or at any rate is only under low pressure. If necessary, it could be provided with a safety valve discharging at a point where provision can be made to avoid danger.

The cock may desirably be constructed on the lines of Patent No. 2,751,185, in which case the fluid pressure has access to the plug side of the ring by a counter-bore in the ring which is of greater diameter than the internal diameter of the abutment against which the outer part of the flexible diaphragm is pressed by the fluid pressure.

An embodiment of the present invention is illustrated by way of example in the accompanying drawing, which is an axial section.

The general construction of the valve illustrated is very similar to that disclosed in my Patent No. 2,751,185. It comprises a body 11, a plug 12 of spherical form, seating rings 13 sealed to the body 11 by diaphragms 14 and a washer 15 which limits the area over which the fluid having access to the back of the diaphragm is effective to press them towards the plug. The effective diameter over which the fluid has access to the back of the diaphragm is the internal diameter of the washer 15 and has been marked B in the drawing. The fluid pressure also has access between the rings 13 and the plug 12 by way of a counter-bore indicated at 16 in the rings. The effective diameter of the counter-bore has been marked A in the drawing and in the construction according to the present invention diameter A is greater than diameter B, so that the net effect of the fluid pressure acting along is to lift the rings 13 away from the plug 12. To maintain sealing contact springs 17 are used and since larger spring pressures are necessary than in construction disclosed in my Patent No. 2,751,185 aforesaid, it is convenient to provide a series of helical compression springs arranged in circular formation, these springs being located in pockets 18 in metal ring members 19, each having a tubular extension 21 centered in the diaphragm 14 and seating ring 13. Desirably the inner margin of the diaphragm is of dove-tail section on the ring side as at 22 so that the material is under volume compression thus ensuring a good fluid-tight joint between the diaphragm 14 and ring 13. A similar section as at 23 may be used to clamp the outer margin of the diaphragm between the inwardly extending washer 15 and the end fitting 24 by which connection is made to the pipe-line.

It will be seen that the internal diameter A of the washers 15 is a little greater than the diameter C of the parts of the rings 13 lying within the washers. Thus any fluid in the body space of the cock between the two rings 13 has access to the plug side of the diaphragms 14 and if after excess pressure on the high pressure side has been relieved as above described into the body space, the pressure in the body space builds up to a high value, the fluid will press the diaphragm 14 on the low pressure side back against the action of the springs 17, the tubular extension 21 being a sliding fit in the ring 13 for this purpose. The liquid in the body space escapes between the diaphragm 14 and the ring 13 and between the ring 13 and the tubular extension 21 into the low pressure side of the line, thus relieving the pressure in the body space. The necessary volume of fluid which has to escape to relieve the pressure is quite small espe-

cially in the case of a liquid so that quite a small sliding clearance between the extension 21 and the ring 13 is adequate. In this way the pressure can be relieved by bypassing the plug without any communication to the outside at the location of the valve. The low pressure line must be open to the atmosphere at some point or at any rate provided with some means to limit the maximum pressure. If need be it can be provided with a safety valve at a point where discharge can be allowed without danger.

The invention has been described in its application to a plug cock of symmetrical construction with the passage straight through its body and a spherical ducted plug but it will be understood that the invention is not limited to such an arrangement and is applicable to fluid control valves having a body with a passage therethrough and a ducted obturating member movable between a position in which the passage is obturated and a position in which the duct aligns with the passage, the valve being provided with at least one seating ring surrounding the passage and coacting with the obturating member, the ring being sealed to the body of the valve by a flexible diaphragm.

What I claim is:

1. A valve comprising a body having a passage therethrough, a ducted obturating member movable within the body between a position in which the passage is obturated and a position in which the duct therein aligns with the passage, at least one seating ring surrounding the passage at the high pressure side thereof and coacting with said obturating member, a flexible diaphragm sealed to the body and to the seating ring, the fluid pressure in the passage at the location of the ring having access to the back of the diaphragm and also to a portion of the surface of the ring facing the obturating member, the effective area at the back of the diaphragm to which the fluid pressure has access being less than the area of the portion of the surface of the ring facing the obturating member to which the fluid pressure has access so that the net effect of the fluid pressure is in a direction to lift the ring away from the obturating member, and spring means urging the ring against the obturating member with a force adequate to provide a good seal between the ring and the obturating member when the fluid pressure is not above a determined value corresponding to normal operating conditions.

2. A plug cock comprising a body having a passage therethrough, a ducted plug rotatable in said body between the position in which it obturates the passage and the position in which the duct in the plug aligns with the passage, at least one seating ring surrounding the passage at the high pressure side thereof and having an annulus in contact with said plug, a flexible diaphragm sealed to the body and to the seating ring, the fluid pressure in the passage at the location of the ring having access to the back of the diaphragm and also to a portion of the surface of the ring on the plug side of the ring, the effective area of the back of the diaphragm to which the fluid pressure has access being less than the area on the portion of the plug side of the ring to which the fluid pressure has access so that the net effect of the fluid pressure is in a direction to lift the ring away from the plug, and spring means urging the ring towards the plug with a force adequate to provide a good seal between the ring and the plug when the fluid pressure is not above a determined value corresponding to normal operating conditions.

3. A plug cock as set forth in claim 2 comprising two

sealing rings respectively cooperating with the plug at opposite ends of the duct therein, the diaphragms and rings being separate members the seal between which is effected solely by pressure of the one against the other and any fluid which leaks into the body having access to the plug side of the diaphragm so that if the fluid pressure in the body rises above a predetermined value it forces back the diaphragm sealing the ring on the low pressure side and escapes between the diaphragm and the ring from the body space into the passage on the low pressure side.

4. A plug cock as set forth in claim 2 including an annular abutment rigid with the body located at the plug side of the diaphragm against which the diaphragm bears when the ring is against the plug, the internal diameter of the abutment being less than the internal diameter of the annulus of contact between the ring and the plug.

5. A plug cock as set forth in claim 2 including a sealing ring surrounding the passage in the body at each end of the duct in the plug, an annular abutment rigid with the body located on the plug side of each diaphragm against which the diaphragm bears when the ring is against the plug, the diaphragms and rings being separate members the seal between which is effected solely by the pressure of the one against the other, the internal diameter of the abutment being less than the internal diameter of the annulus of contact between the ring and the plug, and the external diameter of the part of the ring extending through the abutment being of smaller diameter than the internal diameter of any abutment so that the fluid leaking into the body between the rings has access to the plug side of the diaphragm and if its value rises sufficiently can force its way between the diaphragm and ring on the low pressure side.

6. A plug cock as set forth in claim 5 in which the passage through the body is straight and the plug is spherical, the two ring, diaphragm and abutment assemblies being symmetrically dimensioned and disposed.

7. A plug cock as set forth in claim 6 in which the spring means comprises a series of helical springs arranged in circular formation around the passage.

8. A plug cock as set forth in claim 7 also comprising a ring member carried by each sealing ring and diaphragm, said ring member having pockets in which said springs are housed.

9. A plug cock as set forth in claim 8 in which the inner margin of the diaphragm is of dove-tail section and is clamped to the sealing ring by the pressure of the springs acting through said ring member.

10. A plug cock as set forth in claim 2 including a main body portion and a separable end fitting, and a rigid annular abutment held between said main body portion and end fitting and located on the plug side of the diaphragm against which the diaphragm bears when the ring is against the plug, the internal diameter of the abutment being less than the internal diameter of the annulus of contact between the ring and the plug, the outside margin of the diaphragm being of dove-tail section and being clamped between said end fitting and said abutment.
